UNITED STATES PATENT OFFICE.

FRED N. MIZER, OF ELYRIA, OHIO, ASSIGNOR TO THE GENERAL PHONOGRAPH MANUFACTURING COMPANY, OF ELYRIA, OHIO, A CORPORATION OF OHIO.

LOW-SPEED GOVERNOR FOR SPRING MOTORS AND THE LIKE.

Application filed October 31, 1925. Serial No. 66,044.

My invention relates generally to motor driven display devices but relates more particularly to a centrifugal speed governor for such devices.

- 5 An object of my invention is to construct a centrifugal governor for a motor driven display device wherein the speed of rotation of the display table may be confined to a substantially low rate.
- 10 Another object of my invention is to construct a centrifugal governor of the class named which is extremely sensitive in operation whereby the rate of speed at which the table revolves may be maintained at a low 15 predetermined value.

Another object of my invention is to provide means for regulating the rate of rotation of a shaft including a centrifugal governor device which is extremely simple of 20 construction and inexpensive to manufacture.

A further object of my invention is to construct a device of the above named character which may be adjusted to a plurality of 25 different vertical positions whereby the rate of speed control of said device may be varied as desired.

A still further object of my invention is to provide such a device of the above named 30 character which may be readily removed from the shaft on which it is supported.

A further object of my invention is to construct a centrifugal governor device for controlling the speed of rotation of shafts 35 whereby the swinging arms thereof are freely pivotally suspended from a point relatively high with respect to the arms.

Other objects and advantages will become 40 more apparent from the following description of an embodiment of my invention, reference being made to the accompanying drawings forming a part of this specification and in which like characters are employed to designate like parts throughout 45 the same.

In the drawings:

Fig. 1 is a top plan view of a spring motor and gearing associated therewith and also shows my governor device in position.

50 Fig. 2 is a side elevation of the same.

Fig. 3 is a side elevation of the governor, and

Fig. 4 is a plan view of the same, and

Fig. 5 is a section on line 5-5 of Fig. 2.

In the drawings, I provide a motor frame 55 consisting of top and bottom sections 1 and 2 respectively, which are each provided with suitable aligned bearings for rotatably supporting the various gears and other parts forming a part of the motor and governor 60 mechanism.

I have shown a motor of the coiled spring type but it is to be understood that other types of motors such as those having an external source of power, electric motors, etc., 65 may be used to drive the table spindle and governor mechanism.

Referring to Figs. 1 and 2, 3 represents a motor spring retaining drum of the usual type having teeth 4 formed about its lower 70 periphery. The drum 3 is rotatably supported within the frame in suitable bearings 5, into which an end of the spindle 6 seats, and is provided with the usual pawl and ratchet device (not shown). A bevel gear 75 7 is rotatable with the spindle 6 and of a diameter substantially that of the drum meshes with a smaller bevel gear 8 carried on an end of a crank shaft 9. The crank shaft 9 is rotatably mounted in the frame 1 so and is supported in suitable bearings. The other end of the crank shaft is provided for receiving a crank or the like (not shown). Rotary motion imparted to shaft 9 will be transmitted to the spindle 6 through the 85 gears 7 and 8 to wind the usual coil spring carried within the drum 3.

The teeth 4 formed on the lower periphery of the drum, mesh with teeth 10 formed on one end of a spindle 11 which is rotatably 90 carried within the frame. A gear 12 of larger diameter is also rotatable with the spindle 11 and meshes with teeth 13 formed on a spindle 14. The spindle 14 is rotatable in suitable bearings and carries a worm gear 95 15 intermediate its ends. Its upper end extends through the frame to form a table support at 14'.

Supported by a suitable bracket 16 is an 100 adjustable bearing member 17 preferably screw threaded into the bracket and having a seat formed in one end to receive and support the end of worm shaft 18. The other end of the shaft is supported in a similar adjustable member 19 carried by the frame 105 1. A worm 20 is formed on the shaft 18 and is positioned to mesh with the worm gear 15 rotatable with shaft 14. In this manner

power is taken from the shaft 14 to drive the governor mechanism which will presently be described and which is my invention.

The above description is that of the usual 5 spring motor and a gear train operable thereby to impart rotary movement to a tablet supported on the upper end of the shaft at 14.

10 My invention resides principally in a governing mechanism used preferably in connection with a spring motor and gearing as above described, and consists more particularly of a governor and means whereby said governor is operated from the turntable 15 spindle.

The shaft 20 is rotatably supported within the bearings 16 and 19 as shown and is provided with a gear 21 near one end and rotatable therewith. The gear 21 meshes with 20 a worm 22 formed on the governor spindle 23. The governor spindle is rotatably mounted within bearings 23 and 24'. As I have shown the bearing 23 may consist of a member threaded into the frame 1 and having 25 a cupped bearing surface formed in its lower end to seat the upper tapered end of the spindle 23. Suspended from the frame 1 in the area surrounding the axis of the shaft 23 is a member 24 having a lower 30 governor brush engaging surface 25 of sufficient diameter and area to permit the governor brushes to contact therewith.

The governor device consists essentially 35 of a collar or central body member 26 apertured centrally to permit its assemblage upon the shaft 23. This device is shown in detail in Figs. 3 and 4. The collar is provided with a set screw 27 extending radially therethrough and in communication with the 40 central opening so that the device may be adjusted and secured to the shaft by tightening the set screw thereagainst. The collar 26 is slotted radially from its outer circumference toward its center as shown at 28 but 45 the slots extend only to within a short distance from the central opening. Pivotally secured and freely movable within the slots 28 by pins 29 are governor arms 30 each being pivotally suspended at a point near their 50 extreme inner and upper edges as shown more clearly in Fig. 3. Each of the arms 30 is formed preferably of a single piece of metal to provide a depending arm portion 31 and a brush carrying portion 32. The brush 55 carrying portion consists of a strip of metal extending substantially at right angles from the arm portion 31 and is bent backwardly upon itself to securely clamp the brush 33 and is shown more clearly in Fig. 4. The 60 brushes consist of suitable lengths of felt or other suitable material which extend upwardly of the portions 32 a sufficient distance to prevent contact of the top edge of the metal arm with the surface 25 when the 65 governor is revolving. The depending arm

portions are each bent or twisted as shown, so that their lower ends normally abut against the spindle 23 when the governor is idle. The arms are twisted in a manner whereby the lower arm areas will tend to 70 "ride" upon the air as the governor revolves thus furnishing an added "lift" for the arms.

In operation, when the motor is running and the tablet and spindle 14 are revolving, motion is transmitted through gears 15, 20, 21, and 22 to revolve spindle 23 upon which the governor is secured in the desired position by the set screw 27. Upon rotation of the spindle and governor the arms 30 will swing outwardly from the spindle, due to 80 centrifugal force, thus bringing the brush carrying portions and the brushes toward and into contact with the under surface 25 of the member 24. The brushes will continue to revolve in contact with the surface 85 25 thereby limiting the speed of the spindle 23 and consequently spindle 14 through which it is geared. By positioning the collar at a point on the spindle sufficiently close to the member 24 the speed of the tablet may be controlled to a very slow rate per given 90 unit of time. As stated hereinbefore the collar is adjustable along the spindle 23 and if a greater rate of speed of tablet travel is desired the collar is adjusted to a lower position on the spindle relative to the surface 25 of the member 24, since the lower the collar is adjusted, the greater will be the centrifugal force required to lift the arms 30 so that the brushes 33 will contact with the 100 surface 25. It is obvious therefore that by my novel construction I have provided a governor that will permit table speeds over a comparatively wide range, yet may be so adjusted that the desired extremely low tablet speed may be attained. Such a low speed is particularly desirable where it is desired to rotate display tablets or platforms or other supports at an extremely low rate of speed and through the use of a governor constructed in accordance with my invention this low rate of rotation may be easily and accurately attained.

It will be noted also that I have transmitted power from the spindle 14, first through 115 the worm wheel 15 and then to the worm 20. Similarly, I have further transmitted that power to the governor from the shaft 18 through the worm wheel 21 and then the worm 22 on the spindle 23. By this arrangement, which is contrary to the usual manner of transmitting power through a worm and then the worm wheel, I have provided a much more sensitive speed governing mechanism.

125 Various changes in the construction of my apparatus may be resorted to without departing from the spirit of my invention or the scope of the subjoined claims.

1. In a centrifugal governor, a rotatable 130

- shaft, means to rotate the shaft, a collar secured to said shaft, and governor arms pivotally suspended from said collar, said arms being freely movable radially of said collar 5 and being suspended from a point adjacent their upper ends, each of said arms consisting of a twisted depending main arm portion, and a brush carrying portion projecting outwardly from the main arm portion.
- 10 2. In a centrifugal governor, a rotatable shaft, means to rotate the shaft, a collar secured to said shaft, and governor arms pivotally suspended from said collar, said arms being freely movable radially of said collar 15 and being suspended from a point adjacent their upper ends, each of said arms consisting of a twisted main arm portion, a brush carrying portion extending substantially at right angles to said main arm portion, and 20 brushes carried by said brush carrying portions.
3. In a centrifugal governor, a rotatable shaft, means to rotate the shaft, a collar adjustably secured to said shaft, and governor arms pivotally suspended from said collar, said arms being freely movable radially of said collar and being suspended from a point adjacent their upper ends, each of said arms consisting of a twisted depending main arm 25 portion, a brush carrying portion extending outwardly from the main arm portion at a point near the fulcrum thereof and bent upon itself to form a brush holding clamp, and a brush carried by said clamp.
- 30 4. In a centrifugal governor, a rotatable shaft, means to rotate the shaft, a collar adjustably secured to said shaft, and governor arms pivotally suspended from said collar, said arms being freely movable radially of said collar and being suspended from a point adjacent their upper ends, each of said arms consisting of a twisted depending main arm 35 portion, a brush carrying portion extending outwardly from the main arm portion at a point near the fulcrum thereof and bent upon itself to form a brush holding clamp, and a brush carried by said clamp.
- 40 5. In a centrifugal governor, a rotatable shaft, means to rotate the shaft, a collar adjustably secured to said shaft, and governor arms pivotally suspended from said collar, said arms being freely movable radially of said collar and being suspended from a point adjacent their upper ends, each of said arms consisting of a twisted depending main arm 45 portion, a brush carrying portion extending outwardly from the main arm portion at a point near the fulcrum thereof and bent upon itself to form a brush holding clamp, and a brush carried by said clamp, and means for limiting the upward movement of said arms, said means being adapted for engagement with said brushes to limit the speed of rotation of said governor shaft.
- 50 6. The combination with a motor device for use with revolving display supports, of a centrifugal governor, including a rotatable shaft, means to rotate the shaft, a collar adjustably secured to said shaft, and governor arms pivotally suspended from said collar, said arms being freely movable radially of said collar and being suspended from a point adjacent their upper ends, each of said arms consisting of a twisted depending main arm 55 portion, a brush carrying portion extending outwardly from the main arm portion at a point near the fulcrum thereof and bent upon itself to form a brush holding clamp, and a brush carried by said clamp.
7. The combination with a motor device for use with revolving display supports, of a centrifugal governor including a rotatable shaft, means to rotate the shaft, a collar adjustably secured to said shaft, and governor arms pivotally suspended from said collar, said arms being freely movable radially of said collar and being suspended from a point adjacent their upper ends, each of said arms consisting of a twisted depending main arm portion, a brush carrying portion extending outwardly from the main arm portion at a point near the fulcrum thereof and bent upon itself to form a brush holding clamp, and a brush carried by said clamp.
8. In a centrifugal governor, a rotatable shaft, means for rotating the shaft, a collar secured to said shaft, and governor arms pivotally suspended from said collar, said arms being freely movable radially of said collar and being suspended from a point adjacent their upper ends, each of said arms having a twisted depending main arm portions.
9. The combination with a motor device for use with revolving display supports, of a centrifugal governor, a rotatable shaft, means for rotating the shaft, a collar adjustably secured to said shaft, and governor arms pivotally and freely suspended from said collar, each of said arms having a twisted main arm portion.

In testimony whereof I hereunto affix my signature this 15th day of October, 1925.

FRED N. MIZER.
